UNITED STATES PATENT OFFICE.

JULIUS BRENZINGER, OF FAIRFIELD, CONNECTICUT, ASSIGNOR TO THE MAX AMS CHEMICAL ENGINEERING CORPORATION, OF BRIDGEPORT, CONNECTICUT, A CORPORATION OF CONNECTICUT.

MEANS FOR WASHING OR DYEING MATERIAL.

Application filed December 12, 1925. Serial No. 75,093.

This invention relates to a machine for washing or dyeing material, especially material of a strand-like character such as artificial silk threads, and has for its main object and feature the provision of means for carrying on the washing or dyeing operation in a more expeditious manner than has heretofore been possible.

In the accompanying drawings the invention is disclosed in a concrete and preferred form in which:

Fig. 1 is a general view, partly in elevation and partly in section of a machine embodying the invention showing two tanks.

Fig. 2 is a view partly in elevation and partly in section of one of the tanks and devices associated therewith.

Fig. 3 is a view, in elevation, looking in the direction of arrow 3 of Fig. 2.

Fig. 4 is a vertical transverse section of a rotatable member used in connection with the device.

Fig. 5 is a longitudinal sectional view through one of the work holders.

Fig. 6 is a transverse sectional view substantially on the plane of line 6—6 of Fig. 5.

Fig. 7 is a transverse sectional view substantially on the plane of line 7—7 of Fig. 5.

Fig. 8 is a transverse sectional view substantially on the plane of line 8—8 of Fig. 5.

Referring now to the drawings, Figs. 4 and 5, 1 indicates a hollow perforated spool which carries the convolutions of material 2, and this spool is mounted on a hollow perforated work holder 3 that communicates with the interior of a member 4 from which extends exhaust pipe 5 to which a suction device as 6 (Fig. 1) is attached. Member 4 is contained within a tank 7 (Figs. 2 and 3) containing a body of treating fluid 8, and the exhaust pipe 5 leads from the interior of member 4 to a point outside the tank. It will therefore be seen that, suction being applied by device 6 to pipe 5, the treating fluid will be carried over the work or through the convolutions, into the interior of the work holder and out through the exhaust.

Coming now to a more detail description of the device it will be seen that member 4 is a rotatable member suitably mounted within the tank and rotated as by means of worm 9 and worm gear 10. Member 4 may be constructed in many different ways, but, as here shown, it consists of two halves

bolted together as at 11, said halves forming a chamber 12. Mounted on the exterior of said member 4 are preferably a plurality of work holders 3, each of which may conveniently be constructed as follows: 13 indicates a bracket which carries a tubular extension 14 having perforations 15. The bracket is secured to member 4 by bolts or screws passing through openings 16, and, by reason of inlets 17 in member 4, the interior of the work holders communicate with chamber 12. Preferably, tubular extension 14 is of such amplitude that two spools 1 may be carried in tandem as shown in the drawings, and these spools, which may conveniently be perforated cylinders of sheet material, are slipped over the tubular extension, packing rings or gaskets 18 between and at the ends of the spools being used to space and seal the parts, after which an end piece 19 is secured in position by means of screw 20 entering bridge member 21 of the tubular extension. By the foregoing means it will be seen that the treating fluid cannot enter the work holders except by passing through the convolutions. As shown in the drawings, the arrangement of work holders is preferably in duplicate, there being a series of work holders extending from each face of member 4.

Exhaust pipe 5 is here shown as being a stationary pipe and extends from the lower end of the tank and out through the bearings and shaft 22 of member 4. The suction device 6 may, of course, be of any suitable character but preferably an ejector is used, fluid (such as water) under pressure coming through pipe 23 and in passing through ejector 6 creates a suction in a well-understood manner. The treating fluid may be introduced into the tank by means of pipe 24, and to empty the tank a waste pipe 25 controlled by valve 26 is used.

It will be noted, particularly from Fig. 4, that the sidewalls of the rotatable member slope from its axis of rotation toward its periphery, and that said member has centrally of its interior, between the sidewalls, an annular clearance space 25*. Non-rotatable pipe 5 extends into the member in line with its axis of rotation and then interiorly of said member, in the plane of said clearance space, toward the periphery of the member in the direction of the bottom of

the tank. 26* indicate lateral outboard bearings and it will be noted that the work-holders extend laterally adjacent the periphery of said rotatable member.

5 In Fig. 1 the equipment is double, that is two tanks completely equipped are shown, but that, as will be understood, is a mere convenience.

The operation of the complete apparatus 10 consists in rotating member 4 within the tank and at the same time actuating ejector 6, the result being to draw the treating fluid over the work, into the rotatable member and out of the machine. When the machine is used 15 to wash the acid from the threads the foul water may be wasted, but if the machine is used for dyeing, the dye may be returned through pipe 24 or otherwise. If it is desired that the body of liquid in the tank 20 shall reach above bearings 22 it will be understood that said bearings and shafts will have suitable packing to prevent outflow of fluid. The tank may be either completely or partially filled with treating fluid. 25 In case the tank is completely filled the work holders will be constantly immersed and a relatively large amount of treating fluid will be constantly drawn out of the tank. In handling certain materials it may be desirable 30 to lessen the flow of the treating fluid by drawing air in at the same time. This can be accomplished by partially filling the tank so that the work holders will be alternately immersed in the treating liquid and 35 removed therefrom. This will have not merely the effect of slowing down the outflow of treating fluid but may in some cases assist the washing action by drawing air through the work.

40 The means for fastening the work-holder to the carrier (shown in Figs. 5 to 8) form the subject matter of application Ser. No. 73,688 filed December 7, 1925.

I claim:

45 1. A washing or dyeing machine including: a tank for containing a body of treating fluid, a hollow member mounted to rotate, on a horizontal axis, in said tank, a hollow, perforated work-holder carried by 50 said member, the interior of the work-holder communicating with the interior of the member, a non-rotatable exhaust pipe extending from a point outside the tank into the member in line with its axis of rotation 55 and then interiorly of said member toward the bottom of the tank, and a suction device associated with said exhaust pipe.

2. A washing or dyeing machine including: a tank for containing a body of treating 60 fluid, a hollow member mounted to rotate, on a horizontal axis, in said tank, a plurality of hollow, perforated work-holders carried by said member adjacent its periphery, the interior of the work-holders 65 communicating with the interior of the

member, a non-rotatable exhaust pipe extending from a point outside the tank into the member in line with its axis of rotation and then interiorly of said member toward its periphery in the direction of the bottom 70 of the tank, and a suction device associated with said exhaust pipe.

3. A washing or dyeing machine including: a tank for containing a body of treating fluid, a hollow member mounted to rotate on a horizontal axis, in said tank, said member having sidewalls sloping from its axis of rotation toward its periphery and having, centrally of its interior, between the sidewalls, an annular clearance space, a non-rotatable exhaust pipe extending from a point outside the tank into the member in line with its axis of rotation and then interiorly of said member, in the plane of said clearance space toward the periphery of said member in the direction of the bottom of the tank, the suction-device associated with said exhaust pipe, and hollow, perforated work-holding means carried by said member exteriorly thereof adjacent its periphery, 90 the interior of the work-holding means communicating with the interior of the member.

4. A washing or dyeing machine including: a tank for containing a body of treating fluid, a hollow member mounted to rotate, on a horizontal axis, in said tank, said member having sidewalls sloping from its axis of rotation toward its periphery and having centrally of its interior, between the side walls, an annular clearance space, 100 lateral outboard bearings for the member located at its axis of rotation, a non-rotatable exhaust pipe extending from a point outside the tank into the member in line with its axis of rotation and then interiorly of said member, in the plane of said clearance space, toward the periphery of said member in the direction of the bottom of the tank, a suction device associated with said exhaust pipe, and hollow, perforated 110 work-holders extending laterally from the exterior of said member adjacent the periphery thereof, the interior of the work-holders communicating with the interior of said member.

5. A washing or dyeing machine including: a tank, a hollow member mounted to rotate, on a horizontal axis, in said tank, said member having sidewalls sloping from its axis of rotation toward its periphery and having, centrally of its interior, between the sidewalls, an annular clearance space, a non-rotatable pipe extending into the member in line with its axis of rotation and then interiorly of said member, in the plane of said clearance space, toward the periphery of said member in the direction of the bottom of the tank, means associated with said pipe to cause flow of fluid therethrough, and hollow, perforated work-holding means carried 125 130

by said member exteriorly thereof adjacent its periphery, the interior of the work-holding means communicating with the interior of the member.

- 5 6. A washing or dyeing machine including: a tank, a hollow member mounted to rotate, on a horizontal axis, in said tank, said member having sidewalls sloping from its axis of rotation toward its periphery 10 and having centrally of its interior, between the sidewalls, an annular clearance space, lateral outboard bearings for the member located at its axis of rotation, a non-rotatable pipe extending into the member in line 15 with its axis of rotation and then interiorly

of said member, in the plane of said clearance space, toward the periphery of said member in the direction of the bottom of the tank, means associated with said pipe to cause flow of fluid therethrough, and 20 hollow, perforated work-holders extending laterally from the exterior of said member adjacent the periphery thereof, the interior of the work-holders communicating with the interior of said member. 25

Signed at Bridgeport in the county of Fairfield and State of Connecticut this 10th day of December, 1925.

JULIUS BRENZINGER.

CERTIFICATE OF CORRECTION.

Patent No. 1, 678,053.

Granted July 24, 1928, to

JULIUS BRENZINGER.

It is hereby certified that error appears in the printed specification of the above numbered patent requiring correction as follows: Page 2, line 76, claim 3, after the syllable "tate" insert a comma; line 85, after "space" insert a comma, and line 87, strike out the word "the" second occurrence, and insert the article "a"; and that the said Letters Patent should be read with these corrections therein that the same may conform to the record of the case in the Patent Office.

Signed and sealed this 2nd day of October, A. D. 1928.

Acting Commissioner of Patents.

by said member exteriorly thereof adjacent its periphery, the interior of the work-holding means communicating with the interior of the member.

- 5 6. A washing or dyeing machine including: a tank, a hollow member mounted to rotate, on a horizontal axis, in said tank, said member having sidewalls sloping from its axis of rotation toward its periphery
 10 and having centrally of its interior, between the sidewalls, an annular clearance space, lateral outboard bearings for the member located at its axis of rotation, a non-rotatable pipe extending into the member in line
 15 with its axis of rotation and then interiorly

of said member, in the plane of said clearance space, toward the periphery of said member in the direction of the bottom of the tank, means associated with said pipe to cause flow of fluid therethrough, and 20 hollow, perforated work-holders extending laterally from the exterior of said member adjacent the periphery thereof, the interior of the work-holders communicating with the interior of said member. 25

Signed at Bridgeport in the county of Fairfield and State of Connecticut this 10th day of December, 1925.
